COMBINED LETTER OPENER AND MAGNIFIER

Thomas L. Hermann, West Henrietta, N.Y., assignor to Bausch & Lomb Incorporated, Rochester, N.Y., a corporation of New York

Filed June 24, 1964, Ser. No. 80,552

Term of patent 14 years

(Cl. D74—1)

FIG. 1 is a top view of a combined letter opener and magnifier, showing my new design;

FIG. 2 is a side view of said magnifier;

FIG. 3 is an end view taken from the right side of said magnifier as viewed in FIGS. 1 and 2;

FIG. 4 is a perspective view of said magnifier;

FIG. 5 is a cross sectional view of said magnifier taken along the line 5—5 in FIG. 2; and

FIG. 6 is a cross sectional view taken along the line 6—6 in FIG. 1.

The side not shown has substantially the same appearance as the side shown.

I claim:

The ornamental design for a combined letter opener and magnifier, substantially as shown and described.
